Primary Examiner — Jonathan J Han(74) *Attorney, Agent, or Firm* — Kristin D. Wheeler(57) **CLAIM**

The ornamental design for a shoe, as shown and described.

DESCRIPTION

FIG. 1 is a top lateral perspective view of a shoe showing my new design;

FIG. 2 is a front view of the shoe, thereof;

FIG. 3 is a rear view of the shoe, thereof;

FIG. 4 is a lateral side view of the shoe, thereof;

FIG. 5 is a medial side view of the shoe, thereof;

FIG. 6 is a top view of the shoe, thereof; and,

FIG. 7 is a bottom view of the shoe, thereof.

In FIGS. 1–7, the lighter wider spaced broken lines showing portions of the shoe, including the outsole and laces, are for the purposes of illustrating environment and form no part of the claimed design. The long short long dashed broken lines show the claim boundary. The short even closely spaced broken lines represent stitching and are claimed.
